UNITED STATES PATENT OFFICE.

WILLIAM H. ROTTGER, OF FARMINGTON, MISSOURI.

DESIGN FOR AN ATTACHING-PLATE FOR HAMES.

47,967.

Specification for Design.

Patented Oct. 12, 1915.

Application filed April 3, 1915. Serial No. 19,078. Term of patent 14 years.

To all whom it may concern:

Be it known that I, WILLIAM H. ROTTGER, a citizen of the United States, residing at Farmington, in the county of St. Francois and State of Missouri, have invented a new, original, and ornamental Design for Attaching-Plates for Hames, of which the following is a specification, reference being had to the accompanying drawing, forming a part thereof.

The figure is a perspective view of an attaching plate for hames, showing my design.

I claim:

The ornamental design for an attaching plate for hames, as shown.

WILLIAM H. ROTTGER.
